E. H. PEIRCE

STOCKING DARNER

Filed Aug. 15. 1921

Fig. 1

Inventor:
Elizabeth H. Peirce
By Fred Gulsch Herffy.

UNITED STATES PATENT OFFICE.

ELIZABETH H. PEIRCE, OF CHICAGO, ILLINOIS.

STOCKING DARNER.

Application filed August 15, 1921. Serial No. 492,431.

To all whom it may concern:

Be it known that I, ELIZABETH H. PEIRCE, a citizen of the United States, and a resident of Chicago, in the county of Cook and State of Illinois, have invented certain new and useful Improvements in Stocking Darners, of which the following is a full, clear and exact description.

The invention relates to stocking darners and its object is to provide a darning which is provided with both foot and heel knobs which may be conveniently gripped and in which provision is made for relatively adjusting the foot and heel knobs to adapt 15 the darning for use in stockings of different sizes.

The invention consists in the several novel features hereinafter set forth and more particularly defined by claims at the conclusion hereof.

In the drawings: Fig. 1 is a perspective of a darning embodying the invention. Fig. 2 is a longitudinal section. Fig. 3 is a transverse section.

25 The invention is exemplified in a darning which comprises a knob 4 which is of suitable form to fill the toe portion of a stocking, a knob 5 which is shaped to fill the heel portion of the stocking and a stem 6 integral with the knob 5 which is smaller in diameter than the knobs to form a convenient handle or grip, whereby the darning with a stocking on it may be conveniently gripped in and by a hand. The stem extends into a socket 7 in the foot knob 4 and is rotatable and longitudinally movable in the socket. A helical groove 8 is formed in the stem 6 and a pin 9 fixed in the foot-knob 4 extends into the groove 8.

40 When the knobs are relatively rotated, the pin and groove connection will cause the knobs to be adjusted to or from each other to adapt the darning for stockings of different sizes. The inner end 10 of groove 8 is disposed to limit the outward movement of the stem to retain the stem and foot knob in connected relation. The parts of the darning are usually formed of wood or other suitable material.

50 The invention exemplifies an improved darning which is provided with both foot and heel knobs and an intermediate portion of reduced size to form a convenient grip for the hand and in which provision is made for relatively adjusting the foot and heel

knobs to adapt the darning for stockings of different sizes.

The invention is not to be understood as restricted to the details set forth, since these may be modified within the scope of 60 the appended claims, without departing from the spirit and scope of the invention.

Having thus described the invention, what I claim as new and desire to secure by Letters Patent, is;

1. A stocking darning comprising the combination of a knob adapted to fill the front portion of a stocking and having a centrally disposed longitudinally extending socket therein, a knob adapted to fill the heel of said stocking, a reduced cylindrical stem integral with the heel-knob and longitudinally movable into and out of said socket to relatively adjust the knobs within a sufficient range to fit in stockings of substantially different sizes, and means to hold the stem and foot-knob in adjustably connected relation.

2. A stocking darning comprising the combination of a knob adapted to fill the front portion of a stocking and having a centrally disposed longitudinally extending socket therein, a knob adapted to fill the heel of said stocking, a reduced cylindrical stem integral with the heel-knob and longitudinally movable into and out of said socket to relatively adjust the knobs within a sufficient range to fit in stockings of substantially different sizes, and means to adjust the spacing between the knobs by relative rotation thereof and to retain the stem in said socket.

3. A stocking darning comprising the combination of a knob adapted to fill the front portion of a stocking and having a centrally disposed longitudinally extending socket therein, a knob adapted to fill the heel of said stocking, a reduced cylindrical stem integral with the heel-knob and provided with a steep pitched helical groove and longitudinally movable into and out of the socket to relatively adjust the knobs within a sufficient range to fit in stockings of substantially different sizes, and a pin carried by the front-knob extending into said groove to hold the stem and front-knob in adjustable relation.

4. A stocking darning comprising the combination of a foot-knob adapted to fill the front portion of a stocking and having a

centrally disposed longitudinally extending socket therein, a knob adapted to fill the heel of said stocking, a reduced cylindrical stem integral with the heel-knob and provided with a steep pitched helical groove and longitudinally movable into and out of the socket to adjust the knob within a suf-

ficient range to fit in stockings of different sizes, and a pin carried by the front-knob to hold the stem in adjustable relation thereto, said helical groove having one of its ends disposed to retain the stem in the foot member. 10

ELIZABETH H. PEIRCE.
